UNITED STATES PATENT OFFICE.

ROLLIN M. TICHENOR, OF SPRINGVILLE, NEW YORK, ASSIGNOR OF ONE-HALF TO CHARLES PINGRY AND CARLOS WAIT, OF SAME PLACE.

VEHICLE-WHEEL.

SPECIFICATION forming part of Letters Patent No. 244,340, dated July 12, 1881.

Application filed March 26, 1881. (Model.)

To all whom it may concern:

Be it known that I, ROLLIN M. TICHENOR, of Springville, in the county of Erie and State of New York, have invented a new and valuable Improvement in Wheels; and I do hereby declare that the following is a full, clear, and exact description of the construction and operation of the same, reference being had to the annexed drawings, making a part of this specification, and to the letters and figures of reference marked thereon.

Figure 1 of the drawings is a longitudinal section of the hub. Fig. 2 is a transverse section of the same, showing some of the spokes in position.

This invention relates to improvements in hubs for vehicle-wheels.

The invention consists in the construction hereinafter set forth.

In the annexed drawings, A is an axle-box, threaded exteriorly at both ends, as shown at a a' .

B is the outer portion of a sectional hub, having the point-band b , swell b' , and spoke-flange b^2 in one piece. From the last there projects, at the center, a sleeve, b^3 .

C is the inner portion, the sand-band c and swell c' being in one piece and the spoke-flange c^2 separate, formed as a disk, with the bore c^3 to receive the axle-box, and a bead, c^5 , fitting under swell c' . The flanges b^2 and c^2 are dished toward their centers, forming the circular flares b^4 c^4 .

The spokes D have their tenons d dovetailed, as shown. These spokes are seated in a ring, 35 with their tenons resting on the sleeve b^3 , and the hub is screwed tight, clasping the spokes firm.

On the inner face of flange b^2 are formed projections b^5 , which come between the spokes and 40 keep outer portion, B, from turning when the other portion is moved. These projections b^5 are on opposite sides of the hub, and, extending out a short distance, fit into recesses z made in the meeting edges of two spokes.

I am aware that sectional hubs are not new, and that they have been made with separate spoke-flanges, and I only claim my device as set forth in the claim.

I claim—

The combination of axle-box A, threaded at the ends, outer hub portion, B, having a spoke-flange, b^2 , provided with circular flare b^4 and sleeve b^3 , inner hub portion, C, the spoke-flange c^2 of which is separate and has the flare c^4 55 and bead c^5 , and spokes D, with dovetailed tenons I, substantially as described.

In testimony that I claim the above I have hereunto subscribed my name in the presence of two witnesses.

ROLLIN M. TICHENOR.
